ASSIGNORS TO JULIUS KAYSER & CO., OF NEW YORK, N. Y., A CORPORATION OF
NEW YORK.

LADY'S BLOOMERS.

1,277,700.

Specification of Letters Patent.

Patented Sept. 3, 1918.

Application filed September 11, 1917. Serial No. 190,761.

To all whom it may concern:

Be it known that we, ELLEN W. DECKER, a citizen of the United States, and a resident of Mariners Harbor, Staten Island, borough 5 and county of Richmond, city and State of New York, and ARTHUR SCOTT, a citizen of the United States, and a resident of the borough of Brooklyn, county of Kings, city and State of New York, have jointly invented 10 a new and useful Improvement in Ladies' Bloomers, of which the following is a specification, reference being had to the accompanying drawings.

This invention has for its object an improvement 15 in ladies' high grade bloomers whereby they are rendered more comfortable to the wearer and more durable and serviceable in use. Bloomers are used by women largely during athletic, gymnastic or 20 similar strenuous activities in which, owing to the excessive bodily movements and unusual positions assumed, abnormal strains are brought upon the crotch section of the garment, owing to the lateral stretching of 25 the limbs of the wearer, which frequently result in ripping the seam of the inset crotch sections as they have heretofore been made, or rupture of the fabric of the inset, or of 30 the garment itself adjoining the inset. This is peculiarly apt to occur because such violent exercises usually take place during the 35 warm weather when the body perspiration at the waist and hip sections of the wearer is apt to cause the bloomers to cling more or less to the body, thus preventing slipping of the garment which might relieve the strains.

Heretofore so called union suits and garments of a similar character supported from the shoulders of the wearer have been provided 40 with a crotch insert so made as to relieve the wearer of annoying pressure and the garment from undue strains in the event that the wearer should excessively stoop over, or in the instance of unusually stout people, 45 even while sitting down, but in order to accomplish this result the elasticity of the inset piece has always been in vertical, not horizontal or lateral lines, since the strain due to stooping or sitting is exerted vertically only.

The purpose of this invention is diametrically opposed to that just described for a series of reasons: First, the garment we contemplate is the well known ladies' bloomer, 55 which is non-rigidly supported from the

waist of the wearer and not from the shoulders. Consequently, the insert piece is made of such material and in such a manner that its elasticity is in horizontal, not vertical direction. Second, the insert is made of such 60 shape that the mere act of separating the limbs of the wearer will, without producing any strain whatever upon the insert, afford additional material for such separation. Third, should such separation continue beyond 65 the point stated, as for instance, when the wearer is squatting or there is otherwise extraordinary separation of the limbs, then the lateral elasticity of the insert is called into play, and is so ample in amount as to avoid 70 all possibility of rupturing the insert or the garment, or occasioning any binding or uncomfortable bodily effect whether body perspiration, tending to bind the garment about 75 the hips of the wearer, be present or not.

Referring to the drawings, Figure 1 is an elevation of a bloomer embodying our invention, cut away at the lower portion of the legs; Fig. 2 is a plan view of the front of our insert crotch piece, the back being substantially identical therewith; Fig. 3 is a somewhat enlarged vertical sectional view on the line 3—3 of Fig. 1.

In the drawings 1 represents the body of the bloomer, which we prefer to make of warp knitted flat silk piece goods cut to shape and properly sewed or united together to form the garment. 2 is the usual waist band, which may be equipped with elastic or draw string, or otherwise, as preferred. 3 is our improved crotch insert. It is made of warp knitted fabric and of a peculiar shape, that is to say, each insert is made of two substantially identical and continuous parts, both of crescent shape, as shown best in Fig. 2, and the material of which they are made is so cut that the warp threads 4, 4, run in vertical directions, *i. e.*, at right angles to the direction in which the strains are exerted upon separating the limbs of the wearer, so that the maximum elasticity of the fabric is availed of for expansion, and the construction embodies not only the foregoing features, but likewise, owing to the fact that the upper edges 6 of the two parts of the insert are cut on the arc of a circle and that the lower edges 7 are likewise cut upon the arc of a circle, although a flatter arc than that of the upper edges 6, the result is that each half of the insert is 110

crescent shaped, so that the lower lateral extremities, if brought up into a straight line horizontal with the central portion, would result in materially increasing the straight line length of the lower edge without effecting any distention whatever of the insert piece itself, and should further expansion be desired, owing to the fact that the material is practically bias along that edge, the 10 utmost possible extension may be secured without exerting any undue strain upon the insert or the garment. It will of course be understood that the lower edges of the front and rear insert pieces are stitched together 15 as indicated at 7 in Fig. 2.

In addition to the foregoing, it will be noted that since the purpose of our invention is to permit great elasticity in horizontal directions, there being no occasion for 20 elasticity in vertical directions, since bloomers are yieldingly supported from the waist only, that each of our insert pieces extends laterally more than twice as far as it extends vertically, and furthermore that its 25 length, in other words, the amount of elastic material present, increases from above downwardly, just as the degree of strain, in other words, the extension of the limbs of the wearer, increases from above downwardly. Our invention is peculiarly efficient as an improvement in garments of this 30 class because in a manner never before attained, as we believe, the insert, owing to its peculiar construction, efficiently meets all 35 demands which may be made upon it.

As stated above, our insert is composed of two crescent shaped pieces, one for the front and one for the back. They are both continuous without any opening, thus making 40 a closed crotch. We prefer that both of them be doubled or reinforced as shown in Fig. 3. This, however, is not essential. Whether doubled or single, the front and rear pieces are, as stated, stitched together 45 at their meeting edges 7, and each insert piece is continuous throughout its area, without seams, either vertical or horizontal. The front and rear insert pieces are stitched to the garment along the edges 6, as shown, the 50 body of the garment having been first appropriately shaped to receive them.

We call particular attention to the fact that the stitches 7 uniting the lower edges 7 of the front and back insert pieces, do not 55 interfere with the elasticity, because as is usual in making such seams along bias material sufficient slack is left in the stitches, so that during the stretching of the fabric the

stitches will simply separate slightly and upon the release of the stretch will automatically return to normal position. 60

It will be obvious to those who are familiar with such matters that modifications may be made in the details of the construction above described and illustrated and 65 yet the essentials of our invention be retained.

We claim:

1. In a garment supported solely from the 70 waist of the wearer, a front and rear closed crotch insert formed of two crescent shaped pieces of warp knitted fabric united at their lower edges and so combined with the garment that their greatest elasticity is in lateral directions. 75

2. In a garment supported solely from the 80 waist of the wearer, a front and rear closed crotch insert formed of two crescent shaped pieces of warp knitted fabric, each having greater length than width, and united at their lower edges and so combined with the garment that their greatest elasticity is in lateral directions. 85

3. In a garment supported solely from the 90 waist of the wearer, a front and rear closed crotch insert formed of two crescent shaped pieces of warp knitted fabric, each having substantially the same vertical extension and each being at least twice as long as wide, and united at their lower edges and so combined with the garment that their greatest elasticity is in lateral directions. 95

4. In a garment supported solely from the 100 waist of the wearer, a front and rear closed crotch insert formed of two crescent shaped pieces of warp knitted fabric, each having greater length than width and gradually increasing from their upper part to their lower edges, and united at their lower edges, and so combined with the garment that their greatest elasticity is in lateral directions. 105

5. In a garment supported solely from the 110 waist of the wearer, a front and rear closed crotch insert formed of two substantially identical crescent shaped pieces of warp knitted fabric united at their lower edges and so combined with the garment that their greatest elasticity is in lateral directions, each of the pieces being at least twice as long as wide and gradually increasing in length from their upper part to their lower edges. 115

In testimony whereof we have signed our names to this specification.

ELLEN W. DECKER.
ARTHUR SCOTT.
